UNITED STATES PATENT OFFICE

151,562

DESIGN FOR A DICE GAME DEVICE

Ernest E. Southwell, Vallejo, Calif., assignor of one-half to Carl Klotz, Santa Rosa, Calif.

Application February 16, 1946, Serial No. 126,622

Term of patent 14 years

(Cl. D34—5)

To all whom it may concern:

Be it known that I, Ernest E. Southwell, a citizen of Australia, residing at Vallejo, in the county of Solano and State of California, have invented a new, original, and ornamental Design for a Dice Game Device, of which the following is a specification, reference being had to the accompanying drawing, forming a part thereof.

Fig. 1 is a perspective view of a dice game device, showing my new design; and

Fig. 2 is a side elevational view of the same.

I claim:

The ornamental design for a dice game device, substantially as shown.

ERNEST E. SOUTHWELL.
